CLAIM

The ornamental design for a floodlight, as shown and described.

DESCRIPTION

FIG. 1 is a rear perspective view of a floodlight, showing my new design;

FIG. 2 is a front perspective view thereof;

FIG. 3 is a front view thereof;

FIG. 4 is a rear view thereof;

FIG. 5 is an enlarged left side view thereof;

FIG. 6 is an enlarged right side view thereof;

FIG. 7 is a top view thereof;

FIG. 8 is a bottom view thereof;

FIG. 9 is a front perspective view of its combined state;

FIG. 10 is an enlarged detail view of area 10 in FIG. 2;

FIG. 11 is an enlarged detail view of area 11 in FIG. 2;

FIG. 12 is an enlarged detail view of area 12 in FIG. 9;

FIG. 13 is an enlarged detail view of area 13 in FIG. 9; and,

FIG. 14 is an enlarged detail view of area 14 in FIG. 9.

The broken lines in the drawings illustrate the portions of the floodlight, which form no part of the claimed design.

The dash-dot broken line circles in FIGS. 2, 9-14 define the bounds of the enlargements and do not form part of the claimed design.
